UNITED STATES PATENT OFFICE.

ROBERT LEWIS WALTHERS, OF TOMAHAWK, WISCONSIN.

BOUQUET STAY.

Application filed July 31, 1924. Serial No. 737,302.

To all whom it may concern:

Be it known that I, ROBERT L. WALTHERS, a citizen of the United States, and a resident of Tomahawk, in the county of Lincoln and State of Wisconsin, have invented a new and Improved Bouquet Stay, of which the following is a full, clear, and exact description.

This invention relates to bouquet stays and more particularly to a support for bouquets of flowers, ferns or floral designs of any kind, but is particularly adapted for use in floral designs for funeral purposes and the like.

The object of the invention is to provide a stay to which the flowers, ferns and the like can be conveniently secured in any desired position and which is capable of bending or adjustment into any desired length or shape in accordance with the design.

A further object is to provide a stay of this character which can be manufactured and sold at an extremely low price and which will greatly facilitate the formation of funeral designs, bouquets and the like.

With these and other objects in view, the invention consists in certain novel features of construction and combinations and arrangements of parts which will be more fully hereinafter described and pointed out in the claims:

In the accompanying drawings—

Figure 1 is a view in elevation illustrating my improved stay, showing the manner of securing flowers thereto;

Figure 2 is a view in transverse section on the line 2—2 of Figure 1.

1 represents my improved stay which is composed of a single piece of bendable wire and which is, throughout the greater portion of its length, bent backwardly and forwardly providing a large number of return bends so that the body portion of the stay is of general sinuous form.

45 One end of the wire, which constitutes

the normal lower end, is bent forming an eye 2, and the other end, normally the upper end, is bent forming a handhole loop 3, with the extremity of the wire bent upon the main portion of the wire, as shown at 4, 50 to close the loop.

The stems 5 of the flowers or plants 6 are located against, upon, or between portions of the stay and are secured thereto by wires or cords 7 looped around the stems 55 and portions of the stay, or otherwise secured, so that they will be held in the position desired. To lengthen the stay, it is simply necessary to pull the latter longitudinally. To shorten the stay, the same can 60 be contracted longitudinally, and it will, of course, be noted that the stay can be bent laterally in any direction in accordance with the bouquet.

The small eye 2 at the normal bottom of 65 the stay is adapted to support the bouquet in inverted position in a refrigerator or cooling space to prevent wilting, and the larger loop at the normal upper end of the stay is for conveniently handling the bouquet 70 or supporting the same in use.

Various slight changes and alterations might be made in the general form of the parts described without departing from my invention, and hence I do not limit myself 75 to the precise details set forth but consider myself at liberty to make such slight changes and alterations as fairly fall within the spirit and scope of the appended claims.

I claim:

1. A bouquet stay, comprising a portable length of wire, said wire bent into sinuous form intermediate its ends, and at one end having a loop constituting a handle.

2. A bouquet stay, comprising a portable length of wire, said wire bent into sinuous form intermediate its ends, and at one end having a loop constituting a handle and at its opposite end having an eye.

ROBERT LEWIS WALTHERS.
